UNITED STATES PATENT OFFICE.

LOUIS F. STIEHM, OF ROLLING STONE, MINNESOTA.

LIQUID STRAINER.

Application filed July 19, 1926. Serial No. 123,498.

The invention relates to improvements in devices for straining liquids, and aims to provide a new and improved strainer construction which is rather simple and inexpensive, is efficient and easy to operate, and may readily be kept in an absolutely sanitary condition.

With the foregoing in view, the invention resides in the novel subject matter hereinabove described and claimed, the description being supplemented by the accompanying drawing.

Fig. 1 is a vertical sectional view through a strainer constructed in accordance with my invention.

Fig. 2 is a horizontal sectional view on line 2—2 of Fig. 1.

In the drawing above briefly described, illustrating the preferred form of construction, the numeral 3 designates an ovate plate having a plurality of fastener-receiving openings 4 near its edge. This plate is provided with a fluid inlet 5 and with an outlet 6, the latter being disposed in the lobe 7 of the plate. Both the inlet and the outlet are preferably in the form of T-couplings, one branch of each coupling being provided with a removable cap 8, which among other features, permits successful flushing of the device.

A cylindrical strainer, preferably formed of an inner coarse screen 8 and an outer fine screen 9, is provided, both screens being closed at one end as indicated at 10, while they are open at their other ends. These open ends are provided with contacting flanges 11 of ovate form, said flanges having openings 12 which register with the openings 4 and being also formed with passages 13 which register with the outlet 6, these passages 13 being formed in the lobe portions 14 of said flanges 11. The flange ends of the screen 8, it will be observed, are in communication with the inlet 5, so that the liquid to be strained enters first the coarse screen 8 and then passes successively through this screen and the fine screen 9, before it discharges through the outlet 6.

A vertically disposed casing 15 of ovate form in transverse section, surrounds the strainer 8—9 and has its lobe portion 16 in communication with the passages 13. The remaining portion of the casing wall also, it will be observed, is outwardly spaced from the strainer.

The upper end 17 of the casing 15, is

closed and is provided with a removable cap or the like 18 for flushing purposes. The lower end of this casing is open and is provided with an outstanding ovate flange 19 having openings 20 which register with the openings 4 and 12. Suitable fasteners, such as the thumb screws 20, pass through these registering openings to tightly clamp all parts of the device together, and it may here be explained that the flanges 11 are preferably formed of lead, so that a tight connection may be obtained, preventing leakage of liquid.

It will be observed from the foregoing that the invention is of simple and inexpensive construction, yet that it will be efficient and very desirable. The fluid is doubly screened and hence all foreign matter is removed from it. Whenever desired, thorough flushing of the apparatus may be effected by connecting a hose with either of the passages 5—6, or by discharging water into the upper end of the casing 15 when the cap 18 is removed, the caps 8 being taken off whenever such detachment will facilitate the flushing operation. Then too, the entire device may be quickly and easily disassembled for thorough cleaning and sterilizing whenever desired.

I claim:

1. A liquid filter comprising an ovate plate having inlet and outlet openings, one of which is disposed substantially in the center and the other in the lobe of the plate, T-couplings communicating with said openings, caps removably secured to the branches of said couplings which are in direct line with the openings in said plate, a casing of ovate form in cross-section, having an open end secured to said plate and having its opposite end closed and provided with a restricted opening, a removable cap for normally closing said opening, and cylindrical strainers concentrically arranged in said casing over the inlet opening in said plate and spaced from the walls of the casing, said strainers being closed at one end and open at their opposite ends, said open ends being secured to said plate.

2. A liquid filter comprising an ovate plate having a plurality of fastener receiving openings near its edge, said plate having an inlet and an outlet passage, one of said passages being disposed in the lobe of said plate, T-shaped couplings depending by one arm from said plate surrounding said passages and each having a removable cap

at the end of the other arm, with the stems of said coupling threaded for connection with suitable inlet and discharge pipes, a cylindrical strainer closed at one end and having an open end communicating with the other of said passages, said open end being provided with an outstanding ovate flange resting against said ovate plate and formed with fastener-receiving openings registering with the aforesaid fastener-receiving openings, the lobe of said ovate flange having a third passage registering with said one passage, a casing of ovate form in transverse

section surrounding said strainer in spaced relation with the latter, said casing having a 15 closed end and an open end, the latter being provided with an outstanding ovate flange having fastener-receiving openings, and removable fasteners passing through all of said fastener-receiving openings, the lobe 20 portion of said casing extending around the aforesaid third passage.

In testimony whereof I have hereunto affixed my signature.

LOUIS F. STIEHM.
